UNITED STATES PATENT OFFICE.

WILLIAM R. WILLIAMS, OF SALT LAKE CITY, UTAH.

SHOE STRETCHER.

Application filed January 9, 1924. Serial No. 685,168.

To all whom it may concern:

Be it known that I, WILLIAM R. WILLIAMS, a citizen of the United States, residing at Salt Lake City, in the county of Salt Lake and State of Utah, have invented a new and useful Improvement in a Shoe Stretcher, of which the following is a full and complete specification.

This invention relates to a shoe-stretcher having several removable attachments whereby any size or shape of shoes can be stretched at any place desired without stretching all of the shoe.

One object of this invention is to provide a shoe-stretcher with one last that can be used to stretch the shoe in the part desired by using attachment designed for said part.

Another object of this invention is to provide a shoe-stretcher having removable parts thereon that can be removed and another part placed thereon to fit the size or shape of the shoe to be stretched.

Another object of this invention is to provide a shoe-stretcher whereby the shoe can be stretched lengthwise but not sidewise, or it will stretch the shoe sidewise and not lengthwise as the case may be.

With these and other objects in view, my invention consists of the following arrangements of parts which are fully disclosed in the following specification, of which the accompanying drawings form a part, in which, similar letters and numerals refer to like parts throughout the several views of the drawings.

Figure 1 is a plan view of the invention showing all stretching attachments thereon.

Fig. 2, is a view on line 2, Fig. 2.

Fig. 3, is a side view of Fig. 1.

Fig. 4, is a section on line 4-4, Fig. 3.

Fig. 5, is a section on line 5-5, Fig. 1.

Fig. 6, is an end view of the sleeve 9.

Fig. 7, is a side view of the sleeve 9.

Fig. 8, is an enlarged view in section of the nut gear.

Fig. 9, is a view showing one form of button used in stretching a small place on the shoe.

The dotted line A represents the outline of the shoe with the invention placed therein.

1 is the body or last. Within the body is placed the gear case 3 which fits within the hole 3' in the body. The gear case 3 holds the operating mechanism which comprises, a drive shaft 5 which passes through a hole

in the top of the gear case 3. On the lower end of the drive shaft 5 and within the gear case 3 is secured a drive gear 10 which operates the nut gear 11. The nut gear 11 60 operates the rod 16 outward or inward. The sleeve 9 has a projection 8 thereon, said projection fitting within a hole 6 in the lower end of the drive shaft 5. The nut gear has a projection 12 thereon which is 65 journaled in the sleeve 9 and another projection 13 which is journaled in the hole 14 in the gear case 3. To hold the sleeve 9 in place the block 14' is placed thereunder and secured thereunder by screws 15 passing 70 through the bottom of the gear case 3.

The operating rod 16 is placed through the hole 16' in the body 1 entering the threads 17 in the nut gear 11 thence through the sleeve 9 and then out through a hole in 75 the back of the gear case 3 and then entering the threads on the plate 18. This operating rod is made of tubing so that threads can be cut on the outside and on the inside.

The cap 19 has an arm 41 projecting 80 therefrom with threads thereon to be entered on the inside of the operating rod 16 and are riveted therein by the pin 44. This cap is made in any size or shape to fit any make of shoe.

A stretching cap 20 is placed over the cap 19 for stretching or shaping the shoe at the toe. Holes 45 and slots 46 placed within the cap 20 receive the button 21 to stretch a small place at the toe. The cap 20 is made 90 in two sections and hinged together at 48', the outer edge being shaped to fit the toe of the shoe while the inner edge is so formed that it will move outward when the cap 19 is forced therein, thus stretching the toe to 95 the desired shape.

On the sides of the body 1 are openings 22' in which are placed the inner ends of the side stretching arms 23. The outer end is provided with a hole in which the button 21 is placed. The arms are pivoted within the openings 22' by the pin 23'. The inner ends of the arms rest in front of the plate 18 and are moved forward as the plate is moved forward by the operating rod 16.

Slots or openings 22 are formed in the sides of the body 1 in which slides the heel member 31. Located on the heel member are holes 32 and notches 50. The spring 34 is secured at one end to the side of the slots 110 and has a pin 33 in the other end. The pin 33 passes through a hole at the side of the

slot 22 and enters one of the holes 32 in the heel member 31. A pin 36 is placed at the lower edge of the slots 22 and rests back of the notches 50 in such a manner that the 5 notches will catch thereon and prevent said heel member entering said slots in case the pin 33 was broken in stretching the shoe.

Having described the parts of my invention I will explain the operation of same.

10 To make the shoe longer, move the heel section out to the desired length and secure it there by the pins 33. Now place the body 1 in the shoe without the cap 20. After body 1 has been placed in the shoe turn the 15 shaft 5 by the handle 5', thus turning gear 10 which in turn operates the nut gear 11 revolving it around the shaft 16 thus pushing the shaft outward by the threads thereon and putting pressure on the toe and heel to 20 stretch the shoe longer.

When the toe is to be stretched or shaped the same movements are accomplished as above with the addition of the cap 20 and when a small point is to be stretched add 25 the button 21.

To stretch the shoe sideways, attach the arms 23 and the button 21 as described above and turn the drive shaft 5 which operates the mechanism and moves the rod 16 forward drawing the plate 18 forward which presses against the inner ends of the arms moves the outer ends outward thus stretching the sides of the shoe. If only one side is to be stretched only one arm is used.

35 Having thus described my invention what I claim as new and desire to secure by Letters Patent, is:

1. A shoe stretcher having in combination, a body, a gear case within said body, a drive 40 shaft having a gear mounted on the lower end thereof, a sleeve within said gear casing, said drive shaft having a hole in the lower end thereof, said sleeve having a projection thereon, said projection on said 45 sleeve fitting within said hole in said drive shaft, another gear within said casing having projections thereon, one of said projections being journaled in said sleeve and the other said projection being journaled in the 50 side of said gear case, said other gear having threads in the opening thereof, a hollow shaft having threads on the outside thereof and in the inside thereof, said threads on the outside thereof fitting in the threads in 55 said other gear, a toe cap attached to said rod and means for operating said drive shaft.

2. A shoe stretcher having in combination, a body, a gear case within said body, a gear 60 operating mechanism within said gear case, a rod extending from said body, a remov-

able toe cap, one end of said rod passing through said gear case and the other end connected to said toe cap, arms pivotally attached to the side of said body, said arms 65 for stretching a shoe sidewise, said arms being operated by said rod when said rod is moved outward, said body having slots on the sides thereof, a heel member, said heel member sliding within said slots, and being 70 provided with holes therein and notches thereon, a spring secured at one end to said slots and having a pin in the other end thereof, said pin being adapted to fit within one of said holes in said heel member to 75 prevent said heel member from moving within said slots in the stretching of said shoe and means for operating said gear mechanism to expand and contract the shoe 80 stretcher.

3. A shoe stretcher having in combination, a body, a gear case within said body, an operating shaft, said operating shaft entering said gear case, a drive gear secured to the lower end of said operating shaft 85 within said gear case, the lower end of said operating shaft having a hole lengthwise therein, another gear within said gear case driven by said drive gear, a sleeve within said gear case, said other gear having projections thereon, one of said projections journaled in the side of said gear case and the other projection journaled in said sleeve, said sleeve having a pin projecting therefrom, said pin fitted within said hole in the 90 lower end of said operating shaft, said other gear having threads in the opening thereof, a hollow bolt having threads thereon fitted within said threads in the opening of said other gear, said bolt also having threads in 95 the hollow opening thereof, a toe cap, said toe cap having a pin projecting therefrom, said pin having threads thereon to fit said threads in the hollow opening of said bolt, a shoe toe stretcher operated by said toe 100 cap, arms pivotally connected to the side of said body, said arms for stretching a shoe sidewise, one end of said arms resting against a block within said body, the other ends of said arms adapted to contain a button for stretching the shoe sidewise, said 105 block to move said arms outward when the mechanism in the gear case is operated, whereby said hollow bolt when operated stretches the shoe lengthwise or sidewise. a 110 heel member sliding within grooves on the sides of said body, means for adjusting said heel member and means for locking said heel member to said body.

In witness whereof I affix my signature.

WILLIAM R. WILLIAMS.
